UNITED STATES PATENT OFFICE

99,138

DESIGN FOR A TUMBLER OR SIMILAR ARTICLE

Kenneth T. Piper, Chicago, Ill., assignor to Seneca Glass Company, Morgantown, W. Va.,
a corporation of West Virginia

Application January 17, 1936, Serial No. 60,637

Term of patent 14 years

To all whom it may concern:

Be it known that I, Kenneth T. Piper, a citizen of the United States, residing at Chicago, in the county of Cook and State of Illinois, have invented a new, original, and ornamental Design for a Tumbler or Similar Article, of which the following is a specification, reference being had to the accompanying drawing, forming part thereof.

In said drawing:

I claim:—

The ornamental design for a tumbler or similar article, as shown.

KENNETH T. PIPER.
